UNITED STATES PATENT OFFICE.

THOMAS C. KELLY, OF CINCINNATI, OHIO.

DRYING-MACHINE.

1,261,132.

Specification of Letters Patent.

Patented Apr. 2, 1918.

Application filed November 22, 1916. Serial No. 132,920.

To all whom it may concern:

Be it known that I, THOMAS C. KELLY, a citizen of the United States, residing at Cincinnati, in the county of Hamilton and State of Ohio, have invented a new and useful Drying-Machine, of which the following is a specification.

My invention relates to drying machines in which spiral conveyers are used to move the material to be dried over a heated surface, and the objects of my invention are, first, to provide a method of continuously drying pasty material. This is accomplished by having two spiral conveyers with the spirals of the same hand and pitch running together in the same direction and over-lapping so that the spirals of one conveyer will clean the spirals of the other conveyer. These intermeshing spiral conveyers are rotated and arranged appropriately to feed or convey the material in the same direction through a given feed conduit, the depth of intermeshing being sufficient to provide mechanical clearance, and yet serving to mutually clean one another from the wet and rather adhesive material to be dried, and so insuring a uniform and dependable progressive feed under the coördinated intermeshing spiral influence. These spiral conveyers carry the material to be dried over a heated surface thereby drying it. Second, to dry material in a tight casing so as to prevent the escape of dust.

I prefer to pile one conveyer above the other, thus saving floor space and also making one steam space heat the top of one drying space and the bottom of another.

I attain these objects by the mechanism illustrated in the accompanying drawing, in which—

Figure 1 is a horizontal section of the drying machine on line 1 1 Fig. 3. Fig. 2 is a vertical section of the drying machine on line 2 2 Fig. 3. Fig. 3 is a vertical section on line 3 3 on Figs. 1 or 2. Fig. 4 is a detail view showing arrangement of gears for driving the spiral conveyers.

The casing 1 with steam passages 2 and conveyer troughs 3 with vapor space 22, for carrying off moisture which is evaporated in drying the material, constitute the framework of the drying machine which has bearings 8 for the spiral conveyers and bearings 10 for the counter shafts, the steam passages being connected by the side pipes 4.

Steam entering at nozzle 5 and leaving from nozzle 6.

The spiral conveyers 7 (I prefer conveyers with double spirals) in troughs 3 are supported by bearings 8 at each end. On one end of each spiral conveyer is a spur gear 9 for mating into an idler gear 11, for driving the mating conveyer in the same direction. One end of one conveyer shaft of each pair of conveyers is extended for carrying a bevel gear, 12, for driving which mates with pinion 13 on counter shaft 15. This counter shaft 15 is vertical and stands on step box 14, with vertical bearings 10. The counter shafts 15 are driven by bevel gears 16 which in turn are driven by the bevel pinion 17 on the main driving shaft 18. The main driving shaft is driven by pulley 19, power for which is derived from a belt 75 passing around it.

The material in drying is fed in the drying machine at nozzle 20 and carried over the heated conveyer trough 3 by the spiral conveyers 7 whose intermeshing spirals act as self cleaners and prevent clogging of the conveyers by the material in process of drying and when the material is dry it drops out of the nozzle 21 into any appropriate bin or receptacle.

The conveyer trough 3 is heated by steam in the steam space 2.

As is clearly shown in Fig. 1, spirals 7 are intermeshed to coact or unitarily convey, but separated, or non-contacting. They thus operate to work the material upon itself and between the spirals, keeping them clean and also subjecting the material to an attrition type of feed, which disintegrates and breaks up the tenacious lumps, coincident to the heating, producing a product both dry and homogeneously comminuted.

It will thus be seen that I provide a drier comprising a tier of end-wise communicating feed conduits arranged in different horizontal planes, and in the same vertical plane, the intermeshing spiral conveyers feeding alternately in opposite directions from top to bottom in the successive conduits, thus feeding and dropping the wet material step like through the drier, and at the same time subjecting the conveyed material to the influence of a drying current flowing counter to the general direction of run of material through the drier.

The wet material is thus positively moved along at a uniform rate without adhesion

or choking, and at the same time it is most advantageously presented to the counter flow of the drying current.

I claim:

1. In a machine for drying wet material, an inclosed elongated feed conduit, intermeshing conveyers running lengthwise of the conduit and arranged to feed in a given direction through the conduit, and means for directing a drying fluid current through the conduit.
2. In a machine for drying wet material, an inclosed elongated feed conduit, intermeshing conveyers running lengthwise of the conduit and arranged for feeding material in a given direction through the conduit, and means for directing a drying current through the conduit in a direction counter to the conveyer feed.
3. In a machine for drying wet material, a series of inclosed conduits arranged step like and having alternate endwise communication from top to bottom for the feed passage, intermeshing spiral conveyers in each conduit, each intermeshing pair being arranged for feeding endwise of the conduit and arranged to feed successively in oppo-

site direction through the successive conduits from top to bottom and means for subjecting the material under conveyance to a drying agency.

4. In a machine for drying wet material, a series of inclosed conduits arranged step like and having alternate endwise communication from top to bottom for the feed passage, intermeshing spiral conveyers in each conduit, each intermeshing pair being arranged for feeding endwise of the conduit and arranged to feed successively in opposite direction through the successive conduits from top to bottom and means for subjecting the material under conveyance in each conduit to a counter fluid drying current.

5. In a machine for drying and disintegrating wet material, an inclosed, elongated, heated conduit, a pair of intermeshing screw conveyers running longitudinally therein, means for unitarily rotating the screws, the spirals being separated for attrition of material forced between the screws, for drying and disintegrating the material.

THOS. C. KELLY.
